HEAT TREATING FURNACE

Original Filed Oct. 31, 1928

FIG 1

FIG 2

INVENTOR
Josef LUNDBORG

By *Chas. A. Lind*
ATTORNEY

UNITED STATES PATENT OFFICE

JOSEF LUNDBORG, OF TOLEDO, OHIO, ASSIGNOR TO THE SURFACE COMBUSTION CO., INCORPORATED, OF TOLEDO, OHIO, A CORPORATION OF NEW YORK

HEAT-TREATING FURNACE

Application filed October 31, 1928, Serial No. 316,178. Renewed April 2, 1930.

This invention relates to improvements in heat-treating furnaces and has as its general object to provide an improved movable-hearth type of furnace. More particularly it is an object of the invention to provide a furnace of annular form having an endless heating chamber wherein is mounted a rotary annular tray or hearth so arranged that it may be heated from below as well as from above and rotated in a series of steps.

Referring to the drawings wherein the preferred form of the invention is shown:

Fig. 1 is a plan view of the improved furnace, a portion thereof being broken away, 15 and

Fig. 2 is a vertical section through the furnace.

Suitably supported by a frame work 10 is an annular furnace structure forming a heating chamber 12. Supported on and rising from the floor 14 of the chamber are two concentric rows of piers or hearth supports 16. Supported on the piers is an annular hearth or tray 18 of suitable heat-resisting metal. Positioned in the opposite side walls of the heating chamber and firing into the chamber below the hearth are gas burners 20 and 22, the burners being in staggered relation and firing through the radially extending spaces 24 between the piers whereby the hot gases pass under the hearth and up along the opposite side wall and into the top portion of the chamber above the hearth, the latter being of less width than the chamber. Similar burners 26 and 28 may also be positioned in the chamber side walls at a level above the hearth to fire directly into the top portion of the chamber.

In the outer side wall of the heating chamber are suitable openings through which the work to be heat-treated may be entered into and removed from the chamber, the openings being closed by suitable doors 30 and 32.

In the floor of the chamber between the piers are circumferentially spaced arcuate openings 34 wherein are positioned movable upright posts 36 which at their lower ends are secured to the ends of radial arms 38 secured to an upright shaft 40 positioned at the axis of the furnace in suitable bearings

42 and 44. The lower end of the shaft is stepped in a bearing 46 mounted on a horizontally disposed lever 48 pivoted at one end to a support 50 and connected at its other end with an upright link 52. The upper end of this link is connected to a crank arm 54 on the shaft of a speed reducing mechanism 56 which in turn is driven by a motor 58. Rotation of the crankshaft raises and lowers the shaft 40 and hence the posts 36 as will now be readily understood. The length of the individual posts 36 is such that when the shaft 40 is at its lowermost position the tops of the posts 36 are out of contact with the hearth 18 but when the shaft is raised the posts engage the hearth from below and lift it clear of the piers 16. While the hearth is clear of the piers it is given a partial rotation by imparting a partial rotation to the shaft 40 by the following described mechanism.

Secured to the upper end of the shaft 40 is an arm 60 to the outer end of which is connected a link 62 which in turn is connected to a crank arm 64 on the shaft of a speed reducing mechanism 66 driven by a motor 68. For each complete revolution of the crankshaft, the shaft 40 is given a forward and backward rotation, the motors 58 and 68 being so synchronized that when the shaft 40 has been elevated to lift the hearth the shaft 80 is given a forward rotation and vice versa as will now be readily understood. The hearth is, therefore, advanced in a series of steps.

The bottom of the floor openings through which the posts 36 pass are sealed by plates 70 through which the posts pass, the plates being movable with the posts and slidably mounted below the floor opening as will be readily understood. There is no stack connecting with the heating chamber, and consequently there is a plenum of gases within the heating chamber which tends to prevent the entry of air into the heating chamber.

By supporting and moving the hearth as shown and described the hearth and consequently the work resting thereon may be thoroughly heated from below as well as from above and the furnace as a whole constructed at low cost.

What is claimed is:

1. In a furnace, the combination of means forming an annular heating tunnel, an annular hearth within the tunnel, piers extending upwardly from the floor of the tunnel and adapted to support the hearth, and means adapted to raise the hearth from said piers and impart a rotary movement thereto.
2. In a furnace, the combination of means forming an annular heating tunnel, an annular hearth within the tunnel, an upright shaft at the axis of the tunnel, radial arms secured to the shaft and terminating below the floor of the tunnel, upright posts at the outer ends of said arms, said posts projecting through the floor of the tunnel and adapted to take the burden of the hearth, and means for periodically elevating and imparting a rotary motion to said shaft.
3. In an annular heating furnace, a rotatable tray within said furnace, a vertically disposed shaft at the axis of the furnace, a bearing in which said shaft is stepped, means for elevating said bearing to elevate the shaft, means for turning said shaft, and means connected to said shaft for elevating and turning said tray as the shaft is elevated and turned.
4. In apparatus of the character described, the combination of a flat annular tray, a heating chamber wherein said tray is positioned, the bottom of said chamber being provided with a series of circumferentially spaced slots, upright posts individual to each slot, a common support for said posts, and means for vertically and horizontally reciprocating said support whereby the tray may be given a step by step rotation.
5. In apparatus of the character described, the combination of a flat annular tray, a heating chamber wherein said tray is positioned, the bottom of said chamber being provided with a series of circumferentially spaced slots, means rising from the bottom of said chamber for supporting said tray thereabove, upright posts individual to each slot, a common support for said posts, and means for vertically and horizontally reciprocating said support whereby the tray may be given a step by step rotation.

50. In testimony whereof I affix my signature.
JOSEF LUNDBORG.
